UNITED STATES PATENT OFFICE.

HERMAN F. TROMPETER AND JOHN P. BROWN, OF TOPEKA, KANSAS.

SWIVEL FOR TELEPHONE RECEIVERS.

Application filed August 27, 1925. Serial No. 52,796.

Our invention relates to a swivel for telephone receivers, and has for its chief object a mechanism that will prevent the receiver cord from being twisted, causing undue wear 5 thereof.

The mechanism herein disclosed consists of an attachment that can be applied to an ordinary telephone receiver without injuring the part to which it is attached.

10 Referring to the drawings:

Fig. 1 is an enlarged elevation of an ordinary telephone receiver equipped with my device, partly in section for convenience of illustration.

15 Fig. 2 is a plan view of the attachment.

Fig. 3 is a plan view of the insulation cap.

Fig. 4 is a plan view of the metal housing.

Fig. 5 is a plan view of the rotatable member.

20 Fig. 6 is a bottom plan view of the metal housing head.

In Fig. 1, 1 is the housing of the telephone receiver, 2 is the magnet contained therein. To attach our invention we cut out the top 25 of the housing large enough to receive a metal housing 3, the said housing being annular in shape and threaded on the exterior as at A and A', the latter being adapted to screw into the cord receiving end of the 30 housing 1 as shown in Fig. 1. On the opposite end we have provided an insulation cap 4, same being threadedly connected to the housing as at A functioning as insulation for the metal parts hereinafter de- 35 scribed, and the said cap joins snugly to the end of the receiver housing as at B.

As an accurate means for the positioning of the metal housing 3 within the cap 4 we have provided an annular tongue 5 integral 40 with said housing 3, the said tongue functioning as a stop engaging on the cord receiving end of the phone receiver housing and in a groove C in cap 4.

A head 6 threadedly engages into the end 45 of the metal housing 3. Concentrically positioned therein is a binding post 8, the said post being separated from the head by insulation 7. The said post connects with one side of the magnet as at D and the other 50 side E connects with the head as at F.

In the opposite end of housing 3 is a member 9, said member is adapted to rotate in said housing having its bearing on an annular flange as at 10. The said member 55 extending outward engages through the apertures 11 and 12, said apertures being

centrally disposed in the housing 3 and cap 4. The said rotatable member has an aperture 13 adapted to receive the end of the phone receiver cord, one line of said cord 60 closing the circuit with E of the magnet through the medium of housing 3 heretofore described. The adjacent line connects to binding posts as at H closing the circuit through a coil spring 14 which is pivotally 65 seated on the binding post 8 which connects with the magnet line D. The spring functions also as tensioning means for the swivel engagement on the annular flange 10. The said flange being narrow at its point of contact reduces the friction so that the said member 9 will revolve easily.

70 It will be understood that the insulation member 15 is firmly attached to the inner end member 9 by means of screws as shown at 16 and rotates with said member. The spring being the circuit closing means during the rotations.

Our invention may be applied to other 80 parts of the phone system where cords or other connecting means are employed, and where cords and other means may connect to light fixtures or electric heaters of any description. The swivel will function to the same purpose as herein set forth.

85 Such modifications may be employed as lie within the scope of the appended claims.

Having thus described our invention, what 90 we claim as new and desire to secure by Letters Patent is:—

1. In a swivel for a telephone receiver, in combination with a telephone, a housing threadedly connected to the outer end of the receiver, a rotatable member engaging in the housing, a cap threadedly engaging on the outer end of the housing, a receiving cord attached to the rotatable member, a spring tensioning means between the housing and the rotatable member for contact of said members, and to function as circuit closing 95 means between the telephone and the receiver.

100 2. In a swivel for a telephone receiver, in combination with a telephone receiver, a flanged housing attached to the cord receiving end of the receiver, an annular tongue concentrically positioned on the periphery thereof as separating means from the ends when threadedly engaging in the end of the receiver, a cap threadedly engaging on the outer end of the first said housing seating 105 110 on the tongue in the end of the receiver, a

head for the housing threadedly engaging therein, a cord receiving member rotatably engaging in the housing functioning as an electric contact closing the circuit between the telephone and the receiver, a member closing the inner end of the rotatable member, a spring axially positioned and carried by said member functioning as a tensioning means for the engagement of the cord receiving member with the housing for continuous contact during rotations.

3. In a swivel for a telephone receiver, in combination with the electric wiring in the receiver, a housing threadedly engaging in the cord receiving end of the receiver, a head threadedly engaging in the inner end of the housing, an insulated binding post axially positioned in the head functioning as a pivot bearing at the inner end, and the outer end as a binding means for one side

of the circuit, a binding post connecting to the head as a circuit closing means for the other side of the circuit, an inwardly extending annular flange on the opposite end of the housing from the head, a rotatable cord receiving member having an outwardly extending flange on the inner end thereof to contact with the said flange, a member to close the inner end of said rotatable member, a spring tensioning means attached to last said member, the opposite end of the spring pivotally engaging on the insulated binding post as circuit closing means between the housing and the rotatable member, an apertured cap threadedly engaging on the cord receiving end of the receiver housing, all as, and for the purpose described.

HERMAN F. TROMPETER.
JOHN P. BROWN.
